UNITED STATES PATENT OFFICE

THEODORE L. HOWELL, OF NEW YORK, N. Y., ASSIGNOR TO KURT VERSEN, OF NEW YORK, N. Y.

DESIGN FOR A LIGHTING FIXTURE

Application filed July 25, 1932. Serial No. 44,438. Term of patent 7 years.

To all whom it may concern:

Be it known that I, THEODORE L. HOWELL, a citizen of the United States, residing at New York city, borough of Manhattan, county of New York, State of New York, have invented a new, original, and ornamental Design for a Lighting Fixture, of which the following is a specification, reference being had to the accompanying drawing, forming a part thereof, in which

Fig. 1 is a perspective view of a position above the bowl of the fixture;

Fig. 2 is a perspective view of the fixture from the working level; and

Fig. 3 is a plan view as the fixture will appear from beneath, or when mounted in a position which would not require the long supporting shaft.

I claim:

The ornamental design for a lighting fixture substantially as disclosed.

Signed at New York, N. Y., this 30th day of June, 1932.

THEODORE L. HOWELL.
